UNITED STATES PATENT OFFICE.

FRANK E. PATERSON, OF CLARKSBURG, WEST VIRGINIA.

APPARATUS FOR PRODUCING CARBON BLACK.

1,244,060.

Specification of Letters Patent. Patented June 22, 1920.

Application filed November 21, 1919. Serial No. 339,716.

To all whom it may concern:

Be it known that I, FRANK E. PATERSON, a citizen of the United States, residing at Clarksburg, in the county of Harrison and State of West Virginia, have invented a new and useful Apparatus for Producing Carbon Black, of which the following is a specification.

My invention has reference to an improved apparatus or machine for producing carbon black and more particularly from natural gas, and resulting from the collection caused by the contact of a flame with a surface.

Among the objects of the invention are to provide an improved construction or machine for the above purpose which may be readily set up and operated; to provide angular contact surfaces designed to result in the flame striking or impinging against the surfaces at the proper degree of angle off of the horizontal to produce a high flowing grade of carbon black; to provide a novel arrangement of burners and means of adjusting the same toward and away from said surfaces to give the proper quality of carbon black and produce a maximum quantity per unit of gas; and to provide novel means for removing the carbon and discharging the same as collected.

With the above objects and others in view, as will appear as the specification proceeds, the invention comprises certain novel combinations and arrangements of parts as will be hereinafter more particularly set forth, it being understood that the device herein described is mainly illustrative of one of the various modifications that may be resorted to within the scope of the device as claimed.

40 In the accompanying drawings:

Figure 1 is a sectional side elevation of my improved carbon machine.

Fig. 2 is a cross section thereof.

Fig. 3 is an enlarged detailed sectional view showing the manner of supporting and adjusting the burner pipes, and

Fig. 4 is a detailed view of one of the scraper blades.

Referring to the accompanying drawings in detail, wherein like reference characters designate corresponding parts throughout the several views, 10 designates the upright corner members or side members of a supporting frame which are suitably anchored

at their lower ends in foundation members 55 or bases 11, preferably suitably embedded in the ground, the uprights being removably secured thereto as indicated at 12. The uprights 10 are connected by upper and lower horizontal frame members or runners 60 13 and 14 suitably bolted to said uprights and constituting in conjunction therewith, a supporting structure or framework.

These horizontal frame members are arranged transversely and connect opposed pairs of uprights while said uprights are further connected by longitudinal stringers 15 serving to effectively brace the framework. Connected to the uprights and to the horizontal frame members 14 are diagonal braces 16 which extend from near the upper ends of the uprights to points slightly spaced from the centers of the frame members 14 so as to provide a space between the lower ends of said diagonal braces to receive and support a trough 17 which rests upon the members 14 and said braces. The diagonal braces are connected by longitudinal bars 18 which serve to support a series of sections 19 forming a hopper, said sections 20 having their ends abutting and crimped or otherwise connected so that they may be detached or removed and replaced individually or otherwise when necessary, by reason of being formed of sheet metal as shown. The joints between these sections are designated at 20 and secured to the lower faces at spaced points are clips 21 which removably engage over the bars 18 and thus support the sections of the hopper to discharge onto plates 22 secured between the lower ends of said hopper sections and forming wings of the trough 17 extending longitudinally of the framework of the machine.

A suitable supply pipe 23 for gas, extends 25 along the machine at the base thereof and from this pipe, extends risers 24 including in their structure, slip couplings 25 designed to facilitate connection of the parts and to allow for variation in the lengths thereof. 100 The upper ends of these risers terminate near the top of the hopper, the upper edge of one side thereof being recessed as shown at 26 to accommodate burner feed pipes 27 arranged across the machine at intervals. 105 From these pipes, extend vertical branch pipes 28 leading to the burner pipes or burners 29 extending longitudinally of the ma-

chine in spaced pairs, the burner apertures thereof being designated at 30.

In conjunction with the members 13 which are of inverted T-shaped cross section, the 5 burner pipes are suspended for vertical adjustment and for this purpose the horizontal flanges of a T-bar or T-shaped member 31 as adapted to receive the suitably closed ends of burner pipes 29 and the flanges of the 10 members 13 and the corresponding flange of the bar 31 are connected by vertical bolts or other adjustable members as indicated at 32, so that the ends of the short pipes rest on the flanges and each section of the burners is 15 adjustable independently of the other sections. The members or bars 13 are also designed to support a series of vertical scraper blades 33 which are arranged transversely of the machine in equi-distantly spaced relation and arranged at right angles with respect to each other or at any other suitable angle which may be found better suited to the quality of gas being burned so as to produce a maximum quantity of carbon. The 20 handles of these scrapers are indicated at 34 and are secured to the bars or members 13, said handles having horizontal portions and inclined downwardly extending portions 35.

The uprights of the frame receive rail 30 chairs 36 in which are supported track rails 37 longitudinally of each side of the machine and upon which is adapted to travel a carriage 38 including wheels or rollers 39 journaled therein. The carriage includes 35 transverse bars spaced apart and connected by longitudinal bars 40 having bearings for the trunnions of the wheels 39 which are preferably of the flanged type, and said transverse bars have suspended therefrom 40 a series of right angular plates 41, the opposite sides of which have connected thereto detachably, brackets 42 provided with horizontal portions 43 adjustably suspended from the lower flanges of the bars 38 as by 45 means of bolts 44. By this means, the angular plates extending longitudinally of the machine within the area of the hopper, are supported to be engaged by the scraper blades and as suitable means, not shown, are 50 provided for reciprocating the carriage upon the rails, preferably moving the same a distance of about four and one half feet and then automatically reversing the direction of movement thereof, it will be seen 55 that by adjustment of the scraper blades or plates, or both, the scraper blades will properly conform to the surfaces of the angular plates and scrape the carbon black off of the same. The advantage of the angular 60 plates is that a burner is disposed beneath each side and the flames strike the plates at the proper angle to produce a high flowing grade of carbon black.

Also, as the carbon black is removed, it 65 will fall into the hopper and consequently

into the trough 17 to be carried or conveyed to one end of the machine through the medium of a suitable carrier such as a screw conveyer 45. The advantage of having the hopper shaped as described and substantially closed at the bottom, is to protect the flames against drafts of air, thereby insuring a steady blaze and a maximum production of carbon black. It is of course understood that any carbon black which falls before being removed by the scrapers, will drop into the hopper and be carried off as described and that the quality of the carbon black can be varied by raising or lowering the burners, which adjustment can be very 80 easily accomplished.

What is claimed is:—

1. A machine or apparatus for producing carbon black comprising a support, a hopper carried by the support, a gas supply 85 pipe longitudinally of the hopper and having portions thereof extending across the hopper, burners connected to the said portions, plates above said burners and means for varying the distance between the burners and plates.

2. An apparatus for producing carbon black, comprising a supporting frame, including diagonal braces, a hopper removably supported thereon, a conveyer in the 95 trough of said hopper, burners above the hopper and having connection with a supply pipe for gas, a carriage movable above the hopper, right angular plates suspended from said carriage, means for vertically adjusting 100 the burners and plates relatively, scraper blades conforming to said plates and beneath the same in V-shaped formation or substantially so and means to reciprocate said carriage.

3. A machine or apparatus for producing carbon black comprising a supporting frame, a supply pipe for natural gas along the base of the same, risers extending from said pipe, a hopper supported in the frame and including inclined sides having a trough at the lower end thereof, a conveyer in said trough, transverse pipes leading from said risers across the hopper near the top thereof, longitudinal burners having connection 115 with said transverse pipes and supported in the frame for vertical adjustment, scraper blades also supported by the frame, handles for said blades, outwardly and upwardly branching plates above the burners with 120 which the flame is adapted to contact for the formation of carbon black and means for moving the plates relative to the blades to remove the carbon black from said plates and discharge the same into the hopper and 125 conveyer.

4. A machine for producing carbon black comprising a series of spaced parallel supporting beams, burner pipes having closed ends mounted on the flanges of said beams 130

and arranged in sections, and means for adjusting each section independently of the other sections.

5. A machine for producing carbon black comprising a series of spaced parallel supporting beams, burner pipes having closed ends mounted on the flanges of said beams and arranged in sections; means for adjusting each section independently of the other sections, means for receiving a deposit of

carbon from said burners, means for removing said carbon, and means for receiving and discharging said carbon black.

In testimony that I claim the foregoing as my own, I have hereto affixed my signature in the presence of two witnesses.

FRANK E. PATERSON.
